SOLOMON A. WOODS, OF BOSTON, MASSACHUSETTS, ASSIGNOR TO THE
S. A. WOODS MACHINE COMPANY.

PLANING-MACHINE.

SPECIFICATION forming part of Letters Patent No. 364,329, dated June 7, 1887.

Application filed September 6, 1886. Serial No. 212,716. (No model.)

To all whom it may concern:

Be it known that I, SOLOMON A. Woods, of Boston, in the county of Suffolk and Commonwealth of Massachusetts, have made a new and useful invention relating to Planing-Machines, of which the following is a specification.

My invention relates to machines for planing wood and lumber; and it consists in certain new and useful constructions and combinations of the parts thereof, substantially as hereinafter described and claimed.

In the drawings, Figure 1 is a top plan view of a portion of the cylinder, pressure-bars, and the boxes and driving-pulley for the cylinder of a planing-machine. Fig. 2 is a rear elevation of the same. Fig. 3 is a vertical section of the same on the line $x-x$, Fig. 1. Fig. 4 is a side view of one of the sliding blocks which carries the pressure-bar.

2 A is the bed-piece of the machine.

B is the planing-cylinder, designed to dress the lower surface of the board passing through the machine. It is mounted upon a shaft, b, passing through the boxes b' b', which are bolted to the ends of the bed-piece A. The pulley C, mounted upon the shaft b, drives the planing-cylinder from any suitable counter-shaft. It is understood, of course, that the bed-piece A is mounted upon suitable frame-work or legs to sustain it on the floor of the building.

The upright b² at each end of the bed-plate supports the sliding platen D, which is moved up and down by the screw d, journaled in the cross-bar d', which connects the uprights b² at their upper ends on the opposite sides of the machine, extending transversely across it above the platen.

The screw d is provided with the bevel-gear d' at each end of the platen, which is revolved by the bevel-gear d'', mounted upon a horizontal shaft, d', which extends across the machine in the usual manner, and is supported in boxes upon the upper ends of the uprights b². The construction of these parts is well known and will be understood without further description.

E E' are the pressure-bars on each side of the planing-cylinder B, and it is in the manner of mounting and adjusting these pressure-bars that my invention consists. The ends of the pressure-bars and the method of mount-

ing the same are alike in all essential particulars, and a description of one of them will therefore be all that is necessary to understand the invention.

Upon the inner end of the cap of the shaft-bearing box b' is an elevated block, b⁴, of rectangular form, projecting horizontally from the side of the box for some distance along its inner end. This block serves as a flat bed over the inner end of the box, which can be removed to take off the cap of the box and the cylinder. Upon this block is mounted a second L-shaped block, e, having an elongated slot or hole, e', through its flat portion, and a screw-bolt, e², 65 with a washer under its head, passes down through this slot and is tapped into the block b⁴. The vertical part of the block e laps over the inside face of the block b⁴, and has in it a mortise open on top and toward the pressure-bar, and a tenon on the pressure-bar fits loosely into this mortise, being of considerably less depth than the mortise, so as to allow the pressure-bar to be adjusted up and down in the latter. This tenon is lettered e³, and the mortise e⁴, 75 as shown in Fig. 1. A screw, e⁵, is tapped through the tenon of the pressure-bar and rests on the lower wall or face of the mortise, thus sustaining the pressure-bar at any desired height. A check-nut, e⁶, engages with the 80 thread of the screw e⁵ and serves to bind the pressure-bar in any desired position upon the screw. A second elongated slot, e⁷, (shown in dotted lines in Fig. 1,) cut vertically through the sliding block e has a binding-screw, e⁸, 85 tapped into the frame-piece A below it, and passing freely through the slot. The object of forming this block L-shaped and mounting it on block b⁴, as described, is to provide a simple and convenient support for the bar E, 90 which can bring it very close to the cylinder and allow it to be vertically adjusted within the least possible space between the end of the cylinder and its box, thereby materially narrowing the machine-frame without narrowing its cut, and also allowing the platen D to be brought very close to the cutter for dressing thin stuff. The opposite end of the pressure-bar is provided with a similar L-shaped sliding block combined by similar screw-bolts 95 with the frame-work of the machine.

By loosening the screw-bolts e² e³ the press-

ure-bar E may be adjusted nearer to or farther from the planing-cylinder horizontally, and by adjusting the screws e^5 the height of the pressure-bar with relation to the planing-cylinder and the pressure-bar on the opposite side of it may be adjusted, and I thus provide a simple and cheap method of accomplishing these necessary adjustments. The blocks e, being adjustable independently of each other and not extending across the machine, give more room to make the pressure-bar rigid by giving it greater depth.

What I claim as new and of my invention is—

1. The combination of the lower planing-cylinder, B, the pressure-bar E, vertically adjustable in the independent sliding blocks e, and the latter made horizontally and longitudinally adjustable upon the frame-work of the machine.

2. The combination of the lower planing-cylinder, B, the pressure-bar E, provided with projecting lugs e^3 upon its ends, the longitudinally-sliding L-shaped blocks e, provided with mortises in their depending portions, adapted to engage with said lugs, and one or more elongated holes, e^4 , e^5 , and adjusting-screws e^6 , e^7 at each end of the bar, and one or more screws, e^2 , e^8 , to each of said sliding blocks, said adjusting-screws being adapted to adjust the pressure-bar vertically in the sliding blocks and to adjust and secure said sliding blocks horizontally and longitudinally to the frame-work of the machine at each end of the pressure-bar, substantially as described.

SOLOMON A. WOODS.
